UNITED STATES PATENT OFFICE.

ARTHUR R. SANBORN, OF SCHENECTADY, NEW YORK, ASSIGNOR TO GENERAL ELECTRIC COMPANY, A CORPORATION OF NEW YORK.

OVERLOAD DEVICE.

1,323,457.

Specification of Letters Patent. Patented Jan. 20, 1920.

Application filed October 26, 1916. Serial No. 127,806.

To all whom it may concern:

Be it known that I, ARTHUR R. SANBORN, a citizen of the United States, residing at Schenectady, county of Schenectady, State of New York, have invented certain new and useful Improvements in Overload Devices, of which the following is a specification.

My invention relates to devices for controlling electric circuits and has for its object the provision of improved means whereby an electric circuit may be opened and closed in a reliable, safe and efficient manner.

More specifically, my invention relates to an improved device for closing and opening an electric circuit at the will of the operator, and so arranged as to automatically open the circuit upon the occurrence of an overload and to prevent the alternate closing and opening of the circuit until the overload has been removed.

Referring to the drawings which show one embodiment of my invention, Figure 1 shows the structural features of my improved overload device, and Fig. 2 shows the application of my invention of the control of an electric motor; the circuit connections, the overload device and other apparatus being shown diagrammatically for the sake of clearness.

Referring first to Fig. 2, the circuit to be protected and controlled includes the electric motor M having an armature and series field which receive energy from the supply conductors 1 and 2 upon the closing of a circuit including the contactors having the electromagnetically-actuated contacts 3 and 4. The actuating windings 5 and 6, respectively, of these contactors are energized through a circuit including the normally closed overload switch 7 and the pilot or manually operated switch 8. The series coil 9 included in the motor circuit is adapted to raise an armature or plunger 10 in response to an overload in the motor circuit, mechanically raising the overload switch 7 and cause this switch to make electrical contact with the core 11 of a normally deenergized retaining magnet. The coil of this magnet has one of its terminals electrically connected to the core 11 and the other terminal connected through a resistance to the supply conductor 1. When the overload switch 7 is moved into contact with the core

11 upon the occurrence of an overload in the motor circuit, the circuit of windings 5 and 6 is opened, the contacts 3 and 4 are opened and the retaining magnet is energized through a local circuit including the overload switch 7 and the manually operated switch 8. Due to the energization of the coil 12, the overload switch 7 is retained in the upper position until the manually operated switch 8 is opened. When the switch 8 is opened, the coil 12 is deenergized, the overload switch 7 is permitted to drop and the circuit of the windings 5 and 6 is energized when the switch 8 is again closed. The pilot switch 8 may be located at any convenient place, and this is usually at a remote point from the motor, the contactors and the overload device.

Referring now to Fig. 1, showing the structural features of the preferred form of my overload device, the series overload winding 9 is supported in any suitable manner in the casing 13 secured to the base 14. The armature or plunger 10 of the overload device is supported in the coil 9 by means of an arm 15 secured to the casing 13 by means of the bolt 16. A slot in one end of this arm permits an adjustment of the arm and the position of the plunger within the coil so as to adjust the device to open the motor circuit at any value of current desired. The plunger 10 is adapted to coöperate with a stationary core 17 secured to the casing 13 by means of the nut 18. The overload switch 7 is adapted to be mechanically raised by a nonmagnetic extension 19 on the plunger which moves up and down through a hole in the core 17. The retaining magnet 20 has one terminal of its coil 12 electrically connected to the core 11 and the support 21, and the armature 22 for the retaining magnet is secured to the overload switch 7, the arrangement being such that when the overload switch is mechanically raised by the plunger 10 the overload switch opens the circuit of windings 5 and 6 at the electrode 23, and makes electrical connections with the electrode 24 of the retaining magnet, thus energizing the retaining magnet and causing the armature 22 to be magnetically attracted by the core 11 and the circuit for the windings 5 and 6 maintained opened until the manual switch 8 is operated. The overload switch 7 is biased to its lower position by the force of gravity and

by means of a spring 25 or other suitable means.

The operation of my invention is as follows:

- 5 Closing the manually operated switch 8 energizes the windings 5 and 6 of the contactors, the circuit being from the supply conductor 2 through the manually operated switch 8, and the normally closed overload switch 7 through the windings 5 and 6 in multiple to the supply conductor 1. The contacts 3 and 4 will close and the motor circuit will be energized, the circuit being from the supply conductor 1 through the contact
- 10 15 3, the overload coil 9, coil of series contactor 26, starting resistance R, and contact 4 to the supply conductor 2.

The series contactor 26 is of the well known type which is held open when the current through its operating coil is high and is automatically magnetically closed when the current drops to a predetermined value. When, therefore, the armature current drops to the desired predetermined value, the series contactor 26 will close and short circuit the starting resistance R. If at any time the motor circuit is deenergized, as, for instance, upon the occurrence of an overload, the series contactor 26 will open and reinsert the starting resistance R in the armature circuit preparatory to again starting the motor.

It will be noticed that my arrangement requires but one conductor between the manually operated switch 8 and the line contactors, and this is an advantage where remote control is necessary and it is very desirable to limit the number of conductors, as, for instance, on shipboard. With the starting resistance cut out and the motor running at its normal speed, if an overload occurs in the motor circuit, the overload coil 9 will cause the plunger 10 to be raised and the end of the extension 19 will engage the overload switch 7, mechanically lifting the overload switch out of engagement with the electrode 23 included in the circuit of the windings 5 and 6 of the contactors, causing these contactors, as well as the series contactor 26, to open and the plunger 10 to drop. The end of the overload switch will almost immediately thereafter be brought into engagement with the electrode 24 and the coil 12 of the normally deenergized retaining magnet will be energized through a local circuit including the manually operated switch 8, the overload switch 7, core 11 of the retaining magnet, coil 12 of this magnet, through the limiting resistance to the supply conductor 1. With the retaining magnet thus energized, the armature 22 on the overload switch will be attracted by the core 11 and the overload switch held in its raised position until the switch 8 is opened. When, therefore, the motor is stopped by

the occurrence of an overload it will not start again until the attendant returns and opens and recloses the switch 8. The vibration of the overload switch 7 between open and closed position which would otherwise occur due to the continued presence of the overload and which would be a source of danger is thus avoided.

For the protection of circuits where overloads occur infrequently, it is particularly desirable that the retaining magnet for the overload switch be normally deenergized in order to avoid any waste of current, and that when an overload does occur the control switches will be positively opened and maintained opened until the overload ceases. My arrangement is particularly advantageous in these respects, since the retaining magnet 12 is normally deenergized and only energized upon the occurrence of an overload, and the overload switch 7 is directly included in the winding circuit of the control switches and is mechanically opened upon the occurrence of an overload.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

1. The combination with a circuit controlling electromagnetically actuated contactor, of means for opening the contactor and maintaining it open upon the occurrence of an overload, comprising a mechanically opened overload switch magnetically held in its open position by a normally deenergized magnet which is energized when the overload occurs through a circuit including the overload switch.

2. The combination with an electric motor of a contactor for controlling the starting thereof, an overload switch for deenergizing the contactor to stop the motor upon the occurrence of an overload, a retaining magnet energized only when the overload switch is in its operated position and arranged to hold the overload switch open, and a manually operated switch controlling the circuit of the retaining magnet and of the contactor through the overload switch.

3. The combination with an electric motor of a contactor for controlling the starting thereof, an overload switch for deenergizing the contactor to stop the motor upon the occurrence of an overload, a retaining magnet energized only when the overload switch is in its operated position and arranged to hold the switch open, and a manually operated switch for closing the circuit of the retaining magnet through the over-

load switch in its operated position, and for closing the circuit of the contactor through the overload switch in its normal position.

4. The combination with a contactor having a winding adapted to close the same, of a circuit for the winding having therein a normally closed overload switch, a normally deenergized retaining coil for the overload switch, means responsive to an overload for 10 moving the overload switch to open the circuit of the contactor winding and energize the retaining coil through a circuit including the overload switch to prevent the overload switch resuming its normal position 15 after the contactor is opened.

5. The combination with a contactor having a winding adapted to close the same, of a circuit for the winding having therein a normally closed overload switch, a normally deenergized retaining coil for the overload switch, means responsive to an overload for 20 moving the overload switch to open the circuit of the contactor winding and close the circuit of the retaining coil through a 25 circuit including the overload switch to prevent the overload switch resuming its normal position after the contactor is opened, and manually operated means in series with the overload switch for controlling the contactor and the retaining coil.

6. The combination with an electromagnetically actuated circuit controlling contactor and an overload switch for opening the magnet circuit of the contactor to de- 35 energize the controlled circuit upon the occurrence of an overload, of a manually operated switch for controlling the contactor, and a normally deenergized magnet energized, upon the occurrence of an overload, 40 through a local circuit including the overload switch and the manually operated switch for maintaining the magnet circuit of the contactor open until the manual switch is operated.

45 7. The combination with a contactor having a winding adapted to close the same, of a circuit for the winding having therein an overload switch biased to the closed position, a normally deenergized retaining magnet for the overload switch, means responsive to an overload for moving the overload switch to open the magnet circuit of the contactor and close the circuit of the retaining magnet, and an armature on the overload 50 switch coöperating with the retaining magnet to magnetically hold the overload switch in the open position so as to prevent the overload switch closing the circuit of the contactor winding while the retaining magnet is energized.

8. The combination with a contactor having a winding adapted to close the same, of a circuit for the winding having therein an overload switch biased to the closed position, a normally deenergized retaining mag-

net for the overload switch, means responsive to an overload for moving the overload switch to open the circuit of the contactor and close the circuit of the retaining magnet, an armature on the overload switch co- 70 operating with the retaining magnet to magnetically hold the overload switch in the open position so as to prevent the overload switch closing the circuit of the contactor winding while the retaining magnet is energized, and manually operated means for controlling the circuits of the contactor winding and the retaining magnet.

9. The combination with a contactor having a winding adapted to close the same, of a circuit for said winding having therein an overload switch normally biased to the closed position, a normally deenergized retaining magnet for the overload switch, the said retaining magnet having one terminal 85 of its coil connected to its magnet core and the other terminal connected to a supply conductor, means responsive to an overload for moving the overload switch against its bias into electrical contact with the core of the retaining magnet thus deenergizing the winding circuit of the contactor and energizing the coil of the retaining magnet through the overload switch to prevent the overload switch resuming its normal position after 90 cessation of the overload.

10. The combination with a contactor having a winding adapted to close the same, of a circuit for the winding having therein an overload switch normally biased to the closed position, a retaining magnet having one terminal of its coil connected to its magnet core and the other terminal connected to a supply conductor, an armature for the retaining magnet on the overload switch, a relay having an overload coil and an adjustable means for moving the overload switch against its bias into electrical contact with the core of the retaining magnet upon the occurrence of an overload, thus deenergizing the winding circuit of the contactor and energizing the coil of the retaining magnet to attract its armature and prevent the overload switch resuming its normal position after cessation of the overload, and a manually operated switch for controlling the contactor and the retaining magnet.

11. The combination with an electric motor of a contactor for controlling the starting thereof and means for opening the contactor and maintaining it open upon the occurrence of an overload comprising an overload switch for opening the circuit of the contactor upon the occurrence of an overload, an electro-magnet having a winding connected to a circuit which is independent of the contactor winding and arranged to be energized by the opening of the overload switch and a manually operated switch in series with the overload switch 120 125 130

controlling the circuit of the electro-magnet in the open position of the overload switch and controlling the circuit of the contactor winding in the closed position of the overload switch.

12. The combination with a circuit controlling electromagnetically actuated contactor, of a normally closed overload switch for controlling the energization of said contactor, a normally deenergized retaining magnet for maintaining the overload switch in the open position upon the occurrence of an overload, a pilot switch for controlling

the contactor and the retaining magnet, and connections whereby closing the pilot switch 15 energizes the contactor winding through a circuit including the overload switch, and upon the occurrence of an overload the contactor is deenergized and the retaining magnet is energized to hold the overload switch 20 open through a circuit including the pilot switch and the overload switch.

In witness whereof, I have hereunto set my hand this 25th day of October, 1916.

ARTHUR R. SANBORN.
